ATTORNEY

UNITED STATES PATENT OFFICE.

WALTER G. EISENMAYER, OF LOS ANGELES, CALIFORNIA.

DESIGN FOR A BOTTLE.

61,012.

Specification for Design. Patented May 30, 1922.

Application filed September 16, 1921. Serial No. 501,209. Term of patent 14 years.

To all whom it may concern:

Be it known that I, WALTER G. EISENMAYER, a citizen of the United States, residing at Los Angeles, in the county of Los Angeles and State of California, have invented a new, original, and ornamental Design for a Bottle, of which the following is a specification, reference being had to the accompanying drawing, forming part thereof.

The figure is a plan view of a bottle, showing my new design.

I claim:

The ornamental design for a bottle as shown.

WALTER G. EISENMAYER.
